ALBERT S. ALDEN, OF CHICOPEE, MASSACHUSETTS.

Letters Patent No. 87,816, dated March 16, 1869.

IMPROVEMENT IN BIT-STOCK.

The Schedule referred to in these Letters Patent and making part of the same.

To all whom it may concern:

Be it known that I, ALBERT S. ALDEN, of Chicopee, Hampden county, State of Massachusetts, have invented certain new and useful Improvements in Chucks for Braces; and I do hereby declare that the following is a full and clear description thereof, reference being had to the accompanying drawings, and to the letters of reference marked thereon.

In the drawings—

Figures I and III are detailed side views of parts of my invention;

Figures II and IV are corresponding detail end views of the same parts;

Figure V is a sectional side view of the whole; and

Figure VI is an end view of the whole.

The object of my invention is to produce a chuck for bit-braces which shall be easily operated, not liable to get out of order, and cheaply and easily manufactured.

In construction, I form my brace-head, or chuck, of four pieces—a centre, or foundation-piece, C, a sleeve-fastening, A, a nut, I, and a set-screw, 1.

The centre-piece C has, at its end, a square socket, E, tapering inwardly, to receive the shank of the bit.

The piece C is turned with a cylindrical surface extending back about one and a half inch, and upon this the sleeve A fits and works loosely. The sleeve A is intended to be moved longitudinally, as well as rotatorily, its longitudinal movement extending about three-quarters of an inch, and its rotary movement being limited to about one-eighth turn. The stops for these movements of the sleeve are formed by means of a quadrilateral cavity, G, constructed in the surface of the piece C, a screw, 1, being put through the sleeve A, so as to project into this cavity, and stop against its sides, as the sleeve is moved either way, longitudinally or rotatorily.

The rear portion of the piece C is turned much larger than the rest, and coarse threads F are cut upon its surface, with which the corresponding threads H in the nut I mesh.

The arrangement of this nut I is as follows:

The sleeve A, being formed with a partially-closed end, the opening consisting of a square hole, L, of sufficient size to admit the shank of the largest-sized bit, is slid over the cylindrical part M of the centre-piece C, the flange O, on the rear end of the sleeve, forming a shoulder of nearly equal diameter to the threaded portion of the centre-piece C.

The nut I, being formed with an inward flange, P,

at its outer end, sufficiently projecting to catch upon the flange O of the sleeve, is placed over it, and slid back until its threads H engage with those upon the rear of the centre-piece. The screw 1 is now put in place, and the chuck is ready for use.

The operation of securing the bit is as follows:

The square hole L, in the end of the sleeve, is first brought squarely opposite to the socket E in the centre-piece, by turning the sleeve to the desired position. The shank of the bit is then inserted in the socket E, and the sleeve A is turned one-eighth turn, the screw stopping it in the proper place. This brings the sides of the square hole L across the corners of the shank, and in a similar relative position to the square socket E in the centre-piece, as shown in the top view, Fig. VI. The nut I is then turned until it clamps the sleeve tightly down upon the head of the bit-shank, as shown in the sectional view, Fig. V.

The screw 1 performs the double office of forming the stop for both motions of the sleeve, and also of preventing the same from sliding back when there is no tool in, or when it is desired to move it out by turning the nut, it forming a shoulder for the flange of the nut at S.

The bit is taken out by merely reversing the movement of fastening, first turning the nut until the sleeve is unclamped, and then turning the sleeve until the square hole corresponds in position to the square socket E, when the bit can be withdrawn through it.

By this means, I obtain a chuck for braces or other similar devices, which is composed of only four simple parts, and cannot get out of repair by ordinary usage. It is more effective, in holding the bit in place firmly, than any others in the market, in which such simple means are used, and requires no trimming of the bit, if such is made on the well-known and customary patterns.

I am aware of the patent of L. J. Parsons, and the device he claims, and I do not claim the same.

Now, having described my invention,

What I claim as new, and desire to secure by Letters Patent, is—

The bit-brace chuck herein described, consisting of the sleeve A, centre-piece C, and nut I, when all the parts are constructed and arranged to operate as set forth.

ALBERT S. ALDEN.
